UNITED STATES PATENT OFFICE.

FRANCIS H. RICHARDS, OF HARTFORD, CONNECTICUT.

JACQUARD MECHANISM.

SPECIFICATION forming part of Letters Patent No. 573,623, dated December 22, 1896.

Application filed June 8, 1896. Serial No. 594,651. (No model.)

To all whom it may concern:

Be it known that I, FRANCIS H. RICHARDS, a citizen of the United States, residing at Hartford, in the county of Hartford and State of Connecticut, have invented certain new and useful Improvements in Jacquard Mechanism, of which the following is a specification.

This invention relates to Jacquard mechanism, and especially to such a mechanism adapted for use in connection with a key-operated apparatus—for instance, a type-writing machine—and by means of which indications may be selectively recorded on a belt or other device which I hereinafter term a "jacquard," and the latter operated to actuate a driven apparatus controlled by the indications so recorded.

The main object of this invention is to provide a jacquard having two portions, on one of which the desired indications may be recorded and such portion of the jacquard advanced at one rate of speed, and the other of which portions can be actuated independently of the first portion, and differentially relatively thereto, to operate a driven apparatus independently in time and speed with respect to the recordation of the indications of the first portion of the jacquard.

Another object of this invention is to furnish a jacquard having a plurality of settable indicating-actuators shiftable from an unset or non-working position to a set or working position, or vice versa, these indicating-actuators being carried by the jacquard in such a manner that they may be readily moved from one position to the other, and thus permit the selective setting of any desired combination on the jacquard at the will of the operator.

Another important object of this invention is to provide a plurality of key-operated devices operative for recording on one portion of a jacquard successive indications corresponding to the characters controlled by such keys, and a plurality of devices corresponding to such keys and adapted to be operated at another point in the jacquard in accordance with the indications recorded thereon by said keys, it being understood that it is my intention to take off such indications from the jacquard in a machine such as will be hereinafter more particularly described en-

tirely independently in time and speed of the recordation of such indications by the keys of the apparatus. Moreover, as it is obvious that any key-operated apparatus of the general class hereinbefore referred to should be operative to record successive new series of indications upon the jacquard, as successive new combinations of characters, words, &c., are produced by the selective actuation of the keys by the operator, some means must be employed, if an endless jacquard be used, for removing the recorded indications after the operation of the actuated devices controlled thereby. After the indications are recorded by the setting of the indicating-actuators hereinbefore referred to, the removal of such indications will be effective by resetting means operative for restoring such indicating-actuators to their unset positions after the operation of the actuated devices.

As is well understood, the selective operation of the keys which form the keyboard of a type-writing or similar machine is necessarily intermittent, and hence the operation of that portion of the jacquard on which indications are recorded by such keys should also be intermittent. Preferably such portion of the jacquard will advance the same interval on each depression of a key in order that the indications may be regularly spaced thereon. It is not necessary, however, that the operation of that portion of the jacquard at which such recorded indications are utilized to operate the actuated devices or type-controlling devices of the apparatus should be intermittent or should have any special dependence upon the movement of the indication-receiving portion of the jacquard, either with respect to the time when the indications are recorded or the speed with which they are to be taken off at the other portion of said jacquard. I prefer to record these indications on one run, this indication-receiving run being intermittently advanced on the depression of the selected keys, while the other run is normally continuously advanced, so as to operate the actuated devices regularly until a determined series of indications has been taken off and such run has reached the limit of that period of its operation. In the present case I prefer to employ an endless jacquard having a bodily movement endwise in

one or the other direction—due to the differential movements of its respective runs—means being employed for preventing the advance of one or the other of such runs when 5 the jacquard reaches one or the other end of its range of movement, so as to permit the unblocked run to continue to advance and thus carry the jacquard as a whole in the other direction, whereby a balance is maintained at all times between the movements 10 of the two runs and neither run is permitted to continue its advancing movement beyond the corresponding limit of the resultant movement of the whole jacquard until the other 15 run has caught up. It will be apparent, therefore, that if the indications are recorded on one run of the jacquard intermittently and irregularly in point of time, as is generally the case, they will be taken off at the other 20 run independently of the movement of the indication-receiving run and in a regular manner, and hence the operation of the jacquard-actuated devices will not be affected in any wise by irregularities in the speed or touch 25 of the operator.

In the drawings accompanying and forming part of this specification, Figure 1 is a sectional side elevation of a type-writing machine embodying my present invention, parts 30 of the mechanism being broken away to show more clearly the construction. Fig. 2 is a sectional plan of the forward portion of the same with parts removed. Fig. 3 is an enlarged sectional detail side elevation of the 35 Jacquard mechanism of the machine with parts of the general framework removed. Fig. 4 is an enlarged transverse broken sectional elevation looking from the front of the machine, the section being taken in line *a a*, 40 Fig. 3. Fig. 5 is a sectional plan of the front of the machine with the jacquard and the upper portions of the mechanism removed. Figs. 6 to 8, inclusive, are details of the jac- 45 quard and illustrate successive steps in the blocking of the movements of one of the runs and of the actuating devices therefor. Figs. 9 to 11, inclusive, are similar views illustrating the same steps in the operation of disconnecting the actuating mechanism of the other 50 run from such run. Figs. 12 to 15, inclusive, are enlarged detail views illustrating successive steps in the operation of the combined jacquard-actuating and jacquard-actuated apparatus for advancing the indication-trans- 55 ferring run, for transferring the indications to the jacquard-actuated devices, and for restoring the primary jacquard-actuated devices to their normal positions after the setting and operation of the same. Figs. 16 and 60 17 are sectional detail views illustrating the operation of the indicating-actuators of the jacquard by the key-operated devices. Fig. 18 is a detail plan of a portion of the indicating-actuators of the jacquard.

65 Similar characters designate like parts in all the figures of the drawings.

Any suitable framework may be employed

for carrying the several operative parts of the Jacquard mechanism embodying my invention. In the present case this mechanism 70 is illustrated as carried by and embodied in a modified form of the Caligraph type-writing machine.

The main framework is represented comprehending a pair of side frames, such as 2 75 and 2', and a top plate or carrier 3, mounted thereon for supporting the carriage and its platen for movement, step by step, transversely of the machine and for supporting the feed devices usually employed for permitting the feed of such carriage.

At the forward end of the machine the usual Caligraph key-board, having seventy-eight character-keys and two space keys, (each designated in a general way by K,) is 85 represented, each of such keys being shown connected in a suitable manner to key-levers, such as L, of ordinary construction. These key-levers are movable between two extreme positions controlled, respectively, by the 90 stops 7 and 7', and are pivoted on the cross-bar 5, being normally held up against the stop 7' by means of suitable springs, such as 6.

The jacquard which I employ may be any suitable traveler adapted to have indications 95 recorded thereon at one point in its movement and to control by means of such indications the actuation of corresponding operated devices—such, for instance, as the type-arms of a type-writing machine. In the 100 present case the jacquard which I prefer to use is illustrated as in the nature of an endless band or belt capable of rotative and bodily movement, preferably longitudinally of the machine, for the purpose of permitting 105 the actuation of one run thereof differentially relatively to the movement of the other run, although any other form of device having two differentially-movable runs may be employed, if desired.

In the drawings the endless belt or band is shown at J, provided with two circuits of driving-sockets, such as 8 and 8', at its respective opposite sides, the sockets of each circuit being spaced at regular intervals, 115 which interval is the same for both circuits. The walls of these driving-sockets are adapted to be engaged by corresponding teeth or driving members, and two similar driving-gears, such as 9 and 9', are represented carried for 120 rotation, as by means of the rod 10, journaled in the side frames 2 and 2' of the machine, these gears being adapted to coöperate with the walls of such socket for the purpose of advancing the upper run of the jacquard 125 each time the gears are rotated the interval between two teeth.

The operation of the gears 9 and 9' is illustrated herein as effected directly from the keys K by means of a pair of ratchet-wheels 130 11 and 11' in fixed relation, respectively, with the gears 9 and 9', these ratchet-wheels being engaged by pawls, such as 12 and 12', carried by a universal bar controlled by the

keys K, the pawls normally being held in the usual manner in engagement with the teeth of their respective ratchet-wheels. This universal bar is represented at U, extending entirely across the machine beneath and immediately adjacent to the bank of key-levers L and mounted at its ends in a pair of rock-arms 13 and 13', journaled on studs carried by the side frames 2 and 2', springs, such as 14 and 14', being shown also normally holding the rear ends of these rock-arms against corresponding stops 15 and 15'.

It will be apparent from the foregoing that the key-levers, the universal bar, the gears, and the pawls carried by the universal bar constitute actuating means intermittently operative for bodily advancing the jacquard on each depression of a key.

As has been hereinbefore stated, the end-less jacquard is bodily movable for the purpose of permitting the upper and lower runs to be operated at different speeds. In the present case this bodily movement is rendered possible by supporting the jacquard on a carrier mounted on the side frames 2 and 2' and beneath and adjacent to the keyboard of the machine, this carrier being shown guided by suitable ways and movable between two extreme positions, the guides being preferably in the nature of inclined runways supporting and guiding such carrier. The jacquard-carrier is shown in the drawings as a substantially rectangular frame formed by a pair of end pieces or rods 16 and corresponding side pieces or connecting-rods 17, the rods 16 having reduced portions at their outer ends adapted to be engaged by the walls of the runways, such as r and r', in the sides of the main frame. Each of these rods 16 also has mounted thereon a rotary carrier, these carriers being represented in the present instance as drums 18, extending from one side of the main framework to the other, and adapted for supporting the endless jacquard. Said cylinder carriers are preferably rotary, in order to reduce the friction during the rotative travel of the jacquard, but it is obvious that fixed cylindrical carriers might be employed, if desired, and that the jacquard would then slip over the faces of such carriers instead of rotating the same by the rotative jacquard movement.

Any suitable means may be employed for recording the desired indications upon the jacquard as its upper run is caused to advance by the operation of the selected keys. I prefer, however, to record these indications by the setting of selected members carried by the jacquard and movable relatively thereto and adapted to actuate the devices which are controlled by the indications of the jacquard. Hence it will be apparent that my invention contemplates the provision of a jacquard having a plurality of settable members, each adapted to be shifted from one position to another, the setting of these members effecting the recordation of the desired indications

and the set members being operative for actuating settable jacquard-actuated means. These settable members I term "indicating-actuators," as they not only indicate that the operation of a determined device or mechanism may take place, but form the means for operating such actuated part or parts.

It will be obvious that the jacquard will have a plurality of such indicating-actuators, and these are illustrated at p, carried in a circuit extending, preferably, completely around the jacquard. As the upper run of the jacquard has also been described as advanced the same interval at each depression of a key, the indicating-actuators are represented spaced equidistantly longitudinally of the jacquard and carried in transversely-separated longitudinal series, the positioning of the several indicating-actuators being such that they are also arranged in transverse series perpendicular to such longitudinal series.

It will be evident that the indicating-actuators are positioned in the manner just described for the purpose of providing a separate longitudinal series of such actuators for each key-lever and for the further purpose of bringing one indicating-actuator of each of such longitudinal series into position to be operated from its respective key-lever each time the upper run of the jacquard is advanced a space by the actuation of any key. Hence it will be apparent that an indication may be recorded at any point transversely of the upper run of the jacquard on the depression of a key corresponding to such indication, and that on successive actuations of the key-levers a series of indications will be recorded, which may be located at different points transversely of the jacquard.

One form of indicating-actuator adapted to record indications on the jacquard and subsequently to operate jacquard-actuated means is represented in the present case as a jacquard-pin, (see Figs. 3, 4, 16, 17, and 18,) seated in a suitable aperture in the jacquard and oscillatory from such aperture as a center. Each jacquard-pin is preferably formed with a shank portion 19, normally frictionally held by the walls of the aperture in the rubber or leather band which is shown forming the jacquard, and each pin also has an offset portion consisting of a shoulder 19' and is provided with a head 19", parallel with the shank.

I have also illustrated herein setting means for setting a determined number of the indicating-actuators, the setting means being shown selectively operative and in the nature of setting-actuators, such as 20, carried, respectively, by the key-levers L, these setting-actuators having cam-faces, such as 20', adapted to engage the heads 19" of the indicating-actuators to shift or oscillate the same from their normal unset positions to the set positions, in which the indicating-actuators will be operative for moving the jacquard-actuated means. The lower run of the jacquard

is intended to be operated entirely independently of and differentially relatively to the movement of the upper run. For the purpose of so actuating such lower run a continuously-rotative band-wheel is shown at D, carrying a crank or eccentric rod 21, operating a rock-arm 22, fixed on a rock-shaft 23, journaled in the side frames 2 and 2', this rock-shaft also having fixed thereon a rock-frame, 5 hereinafter more particularly described, embodying a rock-arm 24, (see Fig. 5,) having hinged thereto actuating means in the form of a long push-pawl, such as 25, normally held with its point in engagement with the 10 walls of the drive-sockets 8 in the jacquard, the pawl being kept in place by means of a spring, such as 26. It will be seen that at each rotation of the band-wheel D the pawl 25 normally will operate to advance the lower 15 run of the jacquard in the direction indicated by the arrow in Fig. 3, and the throw of this pawl is such that said run will be actuated the interval between two adjacent sockets at each rotation of the band-wheel, so that the 20 lower run will advance with a regular step-by-step movement.

In my present application I have shown the jacquard-actuating means for the lower run as combined with jacquard-actuated means 30 to form a combined jacquard-actuating and jacquard-actuated apparatus having its jacquard-actuating movement operative for independently actuating the lower run of the jacquard and receiving its jacquard-actuated 35 movements from said lower run, and preferably alternately with such jacquard-actuating movement and on the operation of said lower run. This jacquard-actuated means, which will also be referred to as the "primary" jacquard-actuated means, is represented embodying a rock-frame fixed on the rock-shaft 23 and having a plurality of rock-arms, such as 28, (see Fig. 5,) supporting a rock-bar or tumbler-carrier bar, such as 29, 40 carrying a plurality of independently-operative actuated devices or tumblers controlled, respectively, by the respective longitudinal series of indicating-actuators carried by the jacquard. These tumblers are illustrated at 45 t as oscillatory and are normally disposed in unset positions, but are settable by the jacquard, whereby they are oscillated to their set positions, this oscillation being effected in the present case by the direct action of the 50 indicating-actuators, although I do not limit my invention to the operation of such tumblers by means of indicating-actuators traveling with a jacquard. The tumbler-carrier bar is shown in the drawings (see Figs. 4 and 5) as kerfed to form a series of aligned tumbler-separating members, such as 30, having also registering apertures through which a tumbler carrier or rod, such as 31, is illustrated passed, and on which rod the tumblers 55 are supported so as to be independently oscillatory, it being evident that the tumbler-separating members 30 will prevent interfer-

ence of the tumblers with one another and will maintain the same against movement transversely of the machine. It should be 70 understood that the tumblers will be held in frictional engagement with the adjacent faces of the tumbler-separating members, so that when any tumbler is in one position it will have no tendency to move until it is positively 75 actuated.

For the purpose of limiting the movements of the tumblers, stops are provided for stopping the same in their set and unset positions alternately, these tumbler-stops being represented herein carried by the tumbler-carrier bar and preferably between the tumbler-separating members, the stops shown being illustrated at 32 and 32', disposed in pairs, one pair between each pair of tumbler-separating 85 members, the stops of each pair forming, preferably, the rear walls at the bottom of each kerf and converging toward the mouth of such kerf.

The tumblers t are preferably interchangeable, and each of them is represented herein having a face 33, inclined toward the jacquard and adapted to be engaged by its respective indicating-actuator and carried away from the jacquard, the oscillation of the tumbler 90 to its set position being effected by such movement. Each of these faces 33 is also illustrated (see Figs. 3, 4, and 12) having a channel therein in the path of its set indicating-actuator to thereby guide such actuator between the walls of said channel during the travel of the actuator along and over the faces 33. Each tumbler is also shown having a depending arm 34, adapted to operate a secondary actuated device, the movement 100 of such secondary device being accomplished, preferably, after the tumbler is set and not by the setting movement of such tumbler. In the present case the oscillation of the rock-frame carrying the tumblers is utilized to operate the secondary device from the tumbler 105 after the tumbler has been set by its proper indicating-actuator.

In the drawings of this application I have shown the secondary actuated means as operative by the primary actuated means and as consisting of a plurality or bank of devices in the form of type-arm-operating levers L', substantially similar to the key-levers L and corresponding in number with the respective 115 primary actuated devices or tumblers and also with the longitudinal series of indicating-actuators on the jacquard as well as with the key-levers L. Each of the type-arm-operating levers is represented having rising 120 therefrom a finger 35 in position to be engaged by the depending arm 34 of its tumbler when the tumbler is in its set position, this finger being preferably notched at its extremity, as illustrated at 35', to insure the 125 engagement of the arm 34 with such finger during the operation of the type-arm-operating lever by the tumbler.

Each of the levers L' is shown connected

- adjacent to its rear end with a type-arm in the manner usually employed in type-writing machines, and a universal bar controlling the feed mechanism for permitting the step-by-step advance of the carriage across the machine is represented at U', lying directly beneath and adjacent to such levers L', so as to be operated thereby at each actuation of one of such levers.
- From the description of the operating means for actuating the two runs of the jacquard it will be apparent that my invention contemplates the employment of a jacquard having two differentially-progressive portions and a pair of differentially - operative jacquard-movement controllers controlling, respectively, said respective portions of the jacquard and preferably in the nature of differentially - operative jacquard - actuating means for differentially advancing the respective runs of an endless jacquard. It will be seen also that the invention embodies, in connection with a jacquard having differentially-progressive portions or runs, jacquard-actuated means operative by one of said portions or runs, the operation of the jacquard-actuated means by such run taking place independently of the movement of the other run. Moreover, it will be obvious that there are provided means for recording indications on the first run of the jacquard, jacquard-actuating means for actuating such run a determined distance on each recordation of an indication, and jacquard-actuated means controlled at the second run by such indications and operative entirely independently of the movement of the first run. In the preferred form thereof herein illustrated a jacquard is employed having a plurality of settable indicating - actuators normally in their unset positions and shiftable to their set positions, and in order to utilize the indications thereof the jacquard is actuated to bring the indicating-actuators into position for operating settable jacquard - actuated means, such jacquard-actuated means being in inoperative relation with the unset indicating-actuators. Setting means are also advantageously employed for setting a determined number of the indicating-actuators in connection with jacquard-actuating means operative by the actuation of such setting means.
- From the description of the operation of the tumblers and the type-arm-operating levers from the indicating-actuators it will be apparent, also, that I employ, in connection with a jacquard and with actuating means therefor, normally-unset primary jacquard-actuated means normally in inoperative relation with secondary actuated means and settable by the jacquard into position for operating said secondary means, secondary actuated means operable by such primary actuated means, and actuating means for carrying the primary jacquard-actuated means to its operated and operating positions alter-
- nately. The rock-frame and its operating mechanism constitute means for reciprocating or oscillating the primary jacquard-actuated means between such operated and operating positions. The primary jacquard-actuated devices are normally unset, independently settable, in inoperative relation with the unset indicating-actuators, and normally in inoperative relation with the secondary actuated devices, all of the primary jacquard-actuated devices being simultaneously operative to their operated and operating positions alternately, so as to insure the regular setting of the tumblers and a proper sequence of movements for the secondary actuated devices or type-arm-operating levers.
- After the operation of the primary jacquard-actuated means by the set indicating-actuators it is necessary to restore such actuators to their normal positions, in order that new combinations may be set up on the jacquard by the operation of the several keys. Hence some form of indicating-actuator-resetting means constitutes an important feature of my present invention, and I have shown between the jacquard-actuated means and the setting means a fixed bar or resetting-comb, such as R, disposed transversely of the jacquard and secured to the side frames 2 and 2' and embodying a plurality of resetting members, such as 36, (see Fig. 5,) one for each longitudinal series of indicating-actuators, these resetting members being alined, respectively, with such respective series of indicating-actuators. In the present case these resetting members are illustrated having their resetting-faces formed as obliquely-disposed cam-surfaces, such as 36', that portion of each cam-face which is engaged first by the corresponding indicating-actuator after such actuator has set its respective tumbler being positioned directly in the path of such set actuator, while that end of the cam-face at which such actuator passes beyond the resetting member is substantially in alinement with the unset indicating-actuators of its respective series.
- I do not, of course, limit my invention to the use of the particular resetting means just described, as any suitable means may be employed for shifting the indicating-actuators from their working to their non-working positions.
- I have also represented in the drawings (see Figs. 3 and 5 and 12 to 15, inclusive) resetting means for restoring the primary jacquard-actuated means to its normal unset position after the operation of the same; and I have found it desirable to employ, in connection with the jacquard mechanism hereinbefore described, resetting means normally out of the path of the primary jacquard-actuated means and operative into engagement with such actuated means on the return of the primary jacquard-actuated means to its operated position after the operation of the secondary actuated means has been effected.

Referring particularly to Figs. 3 and 5, it will be seen that the resetting means for the tumblers is shown at R', embodying a rock-shaft, such as 37, journaled in bearings in the side frames 2 and 2', said rock-shaft having fixed thereon rock-arms, such as 38, the outer ends of which are represented carrying a resetting-bar, such as 39, extending completely across the machine adjacent to the tumblers and in parallelism therewith.

Another rock-arm is illustrated at 40, secured to the right-hand end of the rock-shaft 37 and hinged by means of a connecting-rod 41 to a link 42, carried by the side frame 2' and having at its outer end an antifriction-roll 43, adapted to travel on the cam-surface 44' of a cam 44, secured to one end of the driving-shaft S, on the opposite end of which the band-wheel or main driver D is fixed.

20 A coiled spring is represented at 45, fixed at one end to the framework and secured at its opposite end to an arm 40', movable with the rock-arm 40 and normally tending to hold the antifriction-roll 43' against the cam-surface 44'.

The operation of a machine constructed in accordance with my invention as hereinbefore described is as follows: On the depression of any key by the operator the corresponding key-lever is actuated and the universal bar U is forced down, carrying with it the pawls 12 and 12', and thereby causing the upper run of the jacquard to be advanced a space, as shown in Fig. 7. At substantially the same time the cam-face 20' of the corresponding setting-actuator 20 engages the head 19' of that indicating-actuator of its respective series which has just been brought into working position by the advance of the upper run, and such indicating-actuator is shifted, as shown in Figs. 17 and 18, from its normal position to a position out of line with the remaining actuators of its series. A determined succession of indicating-actuators may thus be set by the selective operation of the keys without causing the actuation of any of the operated devices adjacent to the lower run, and the setting up of indications on the upper run may be continued until the jacquard and its carrier reach the limit of their movements toward the rear of the machine. At the same time that these indications are being set up the band-wheel D will be normally continuously rotating and regularly carrying the parts controlled thereby in their respective paths of movement, the lower run being carried in the direction indicated by the arrow in Fig. 3 step by step by the push of the point of the pawl 25 as it is engaged in a socket in the under side of the lower run on its forward stroke and is withdrawn therefrom and engaged in the next succeeding socket on its return stroke.

The action of the jacquard will be readily understood by reference to Figs. 1 and 3 and 6 to 14, inclusive. The jacquard frame or carrier is, as before stated, capable of bodily

sliding movement in the slots r' of the main structure, and if, for instance, the upper run or top of the belt is blocked by the engagement of the teeth 9 9' with the drive-sockets 8 8' it is obvious that the lower run or bottom portion of the jacquard will be bodily advanced by the wheel D and the pawl 25 as long as the blocking action continues until either a part or substantially all of the portion of the jacquard between the blocked part thereof and the axis of the drum 18 on the belt is taken up. In this operation, as is obvious, the jacquard frame or carrier 80 slides in the slots r', and the jacquard, of course, slips around the rollers or drums 18 18', whereby the result just set forth may be accomplished.

As soon as those indicating-actuators which have been set at the upper run are brought into operative relation with the tumblers at the lower run by the continued advance of the two runs of the jacquard such tumblers will be selectively carried to their set positions, as shown in Figs. 1, 3, and 12, and will be carried into engagement with the fingers of their respective levers L' and will actuate such levers, (see Fig. 13,) each of the set tumblers being restored to its normal unset position on its rise from engagement with its actuated lever by the engagement of the resetting-bar 39 with such tumbler, as shown in Figs. 14 and 15, the resetting action being fully accomplished before the tumbler has reached the limit of its upward movement.

It will be evident by reference to Figs. 12 to 15, inclusive, that the cam-surface 44' is so shaped that as the antifriction-roller 43 leaves the top of the cam the set tumblers will be forced quickly back to their unset positions by the action of the spring 45. The actuation of the levers L' will of course cause the operation of the type-arms corresponding thereto and of the universal bar U' for permitting the feed of the carriage in a manner well known in the art.

As it is obvious that neither of the runs of the jacquard can be operated uninterruptedly when the two runs are differentially actuated, and especially when, as is the case with the construction described herein, one of the runs is normally continuously operated at a relatively rapid rate of speed, while the other is advanced intermittently at a relatively slow speed, some means must be employed for preventing the advancing movement of each run when such movement has brought the jacquard and its carrier to the limit of their travel in one direction. For the purpose of preventing such advancing movement after the jacquard has arrived at either extreme position I employ a pair of separately-operative jacquard-movement limiters for separately limiting the movements of the respective differentially - progressive portions or runs of the jacquard, these limiters being preferably "jacquard - operated" limiters, movable with and fixed on the jacquard-car-

rier, one of them being illustrated operative for blocking the operation of the intermittently-operative jacquard-actuating means and the other for uncoupling the continuously-operative jacquard-actuating means from the other run. These limiters are illustrated in the drawings as stops carried at opposite ends of the jacquard-carrier, a pair of such stops being shown at 46, rising from the forward ends of the connecting-rods 17, (see Fig. 4,) while a pair of stops, such as 47, depend in a similar manner from the other ends of said connecting-rods. The stops 46 are so disposed that when the jacquard reaches the position shown in Fig. 6 the depression of the key—if the lower run is not simultaneously advanced—will cause said stops to be moved by the jacquard into engagement with the forward faces of depending stops 12", formed integral with the pawls 12 and 12', and on the rise of the pawls when the key is released the ends of the stops 12" will be thrown slightly forward, so that they will lie directly over the stops 46, (see Fig. 8,) whereby the advance of the upper run will be prevented until the lower run has been advanced a distance sufficient to cause the stops 46 to be carried forward out of the path of the stops 12".

The stops 47 operate in a manner substantially similar to that just described. When the jacquard and its carrier reach the position shown in Fig. 9, the next rotation of the driver or band-wheel will advance the lower run the interval between two of the drive-sockets in such run, (see Fig. 10,) and on the return movement of the pawls 25 a pair of pin-stops 25", carried at the points of these pawls, will ride over the corresponding cam-faces 47' of the stops 47, and at the limits of their movements will lie against the stop-faces 47' of said stops 47, thus preventing the points of said pawls from entering the drive-sockets in the lower run. (See Fig. 11.)

It will be obvious that until the jacquard and its carrier have been actuated again toward the rear of the machine by the action of the key-operated devices controlling the upper run the driver D, while continuously rotating, will not impart advancing movements to the lower run, as the continuously-operative driving means is now uncoupled from said run and will be ineffective until the stops 47 are carried to the rear of the pin-stops 25".

As in practice the lower run will be operated continuously at a somewhat faster rate of speed than the upper run will be actuated by the operator, it is apparent that the operator will not have to stop and wait for the lower run to be operated before he can proceed with his work, but that the lower run will, as a rule, advance with sufficient speed to keep the jacquard and its carrier close to the extreme limit of their forward position, as seen in Figs. 9, 10, and 11, and thus give the operator substantially the full length of

the upper run on which to record the necessary indications for operating the type-arms.

While I have illustrated a jacquard having certain described characteristics, my invention is not limited thereto, but includes within its scope any device or mechanism having differentially-progressive portions and provided with means for governing the movements or actuating parts of an adjacent machine.

The details of the jacquard and its co-operative members not herein claimed form the subject-matter of a separate application, filed June 4, 1896, Serial No. 594,248. 80

Having described my invention, I claim—

1. The combination with a device having two differentially-progressive portions and provided with means for actuating adjacent mechanism, of means for operating said device. 85

2. The combination with a device having two differentially-progressive portions and provided with means for actuating adjacent mechanism, of means for differentially advancing said progressive portions. 90

3. The combination with a jacquard having two differentially-progressive portions, of a pair of differentially-operative devices controlling, respectively, said respective portions. 95

4. The combination with a jacquard having two differentially-progressive portions, of a pair of actuating devices operative, respectively, for differentially advancing said respective portions. 100

5. The combination with an endless jacquard having two differentially-progressive runs, of a pair of actuating devices operative, respectively, for differentially advancing said respective runs. 105

6. The combination with a jacquard having two differentially-progressive portions, of intermittently-operative means for actuating one of said portions; and means normally continuously operative for advancing the other portion of said jacquard. 110

7. The combination with a jacquard having two differentially-progressive portions, of a pair of actuating devices normally operative, respectively, for differentially advancing said respective portions of the jacquard; and a pair of devices for separately limiting the movements of said respective portions of the jacquard. 115

8. The combination with a jacquard having two differentially-progressive portions, of a pair of devices normally operative, respectively, for differentially advancing said respective portions of the jacquard; and a pair of limiters for separately limiting the movements of said respective portions of the jacquard. 120

9. The combination with a jacquard-carrying means movable between two extreme positions, of an endless jacquard mounted on said carrying means and having two differ- 130

entially-progressive runs; and a pair of actuating means operative, respectively, for differentially advancing said respective runs.

10. The combination with jacquard-carrying means movable between two extreme positions, of an endless jacquard mounted on and held extended by said carrying means and having two differentially-progressive runs; and a pair of actuating means operative, respectively, for differentially advancing said respective runs.

11. The combination with a carrier movable between two extreme positions, of an endless jacquard supported on and held extended by said carrier and having two runs differentially progressive around said carrier; and a pair of actuating devices operative, respectively, for differentially advancing said respective runs.

12. The combination with a jacquard-operated carrier movable between two extreme positions, of an endless jacquard having two runs differentially progressive around said carrier; and a pair of jacquard-actuating means operative, respectively, for differentially advancing said respective runs.

13. The combination with a jacquard-carrier movable between two extreme positions, of an endless jacquard having two runs differentially progressive around said carrier; a pair of jacquard-actuating means normally operative, respectively, for differentially advancing said respective runs; and a pair of separately-operative limiters for separately limiting the movements of said respective runs at the respective ends of the range of movement of the jacquard-carrier.

14. The combination with a jacquard-operated carrier movable between two extreme positions, of an endless jacquard having two runs differentially progressive around said carrier; a pair of jacquard-actuating means normally operative, respectively, for differentially advancing said respective runs; and a pair of separately-operative limiters movable with the jacquard-carrier for separately limiting the movements of said respective runs at the respective ends of the range of movement of the jacquard-carrier.

15. The combination with a jacquard-operated carrier movable between two extreme positions, of an endless jacquard having two runs differentially progressive around said carrier; a pair of jacquard-actuating means operative, respectively, for differentially advancing said respective runs; and a pair of separately-operative limiters fixed on the jacquard-carrier for separately limiting the movements of said respective runs at the respective ends of the range of movement of the said carrier.

16. The combination with a jacquard-operated carrier movable between two extreme positions, of an endless jacquard having two runs differentially progressive around said carrier; intermittently-operative means for actuating one of said runs; continuously-op-

erative means for normally advancing the other of said runs; and a pair of separately-operative limiters, one for blocking the operation of the intermittently-operative jacquard-actuating means at one end of the range of movement of the jacquard-carrier and the other for uncoupling the continuously-operative jacquard-actuating means from its run at the other end of the range of movement of said jacquard-carrier.

17. The combination with a framework having suitable ways, of a carrier guided by said ways and movable between two extreme positions; an endless jacquard having two runs differentially progressive around said carrier; and a pair of jacquard-actuating means operative, respectively, for differentially advancing said respective runs.

18. The combination with a framework having suitable supporting-ways, of a carrier supported on said ways and movable thereon between two extreme positions; an endless jacquard having two runs differentially progressive around said carrier; and a pair of actuating means operative, respectively, for differentially advancing said respective runs.

19. The combination with a jacquard-operated carrier movable between two extreme positions and embodying a frame and a pair of parallel rotary cylinders carried by said frame, of an endless jacquard supported by said cylinders and having two runs differentially progressive around said carrier; and a pair of actuating means operative, respectively, for differentially advancing said respective runs.

20. The combination with a jacquard having two differentially-progressive portions, of a pair of jacquard-actuating means operative, respectively, for differentially advancing said respective portions of the jacquard; and means actuated by one of said portions of the jacquard.

21. The combination with an endless jacquard having two differentially-progressive runs, of a pair of jacquard-actuating means operative, respectively, for differentially advancing said respective runs of the jacquard; and jacquard-actuated means operative by one of said runs of the jacquard independently of the movement of the other run.

22. The combination with an endless jacquard having two differentially-progressive runs, of means for recording indications on the first of said runs, means for actuating said run a determined distance on each recordation of an indication; means for advancing the second run of the jacquard differentially relatively to the advance of the first run; and means controlled at the second run by said indications and operative independently of the movement of the first run.

23. The combination with a jacquard-belt, of a plurality of settable indicating-actuators carried by said jacquard-belt and normally in their unset positions and shiftable to their set positions; means for actuating the jac-

guard-belt; and means actuated by the set indicating-actuators and in inoperative relation with the unset indicating-actuators.

24. The combination with a jacquard-belt, 5 of a plurality of settable indicating-actuators carried by said jacquard-belt and normally unset; means for actuating the jacquard-belt; means for setting a determined number of said indicating-actuators; and means actuated by the set indicating-actuators and in inoperative relation with the unset indicating-actuators.

25. The combination with a jacquard-belt, 15 of a plurality of settable indicating-actuators carried by said jacquard-belt and normally unset; means for actuating the jacquard-belt; selectively-operative means for setting a determined number of said indicating-actuators; and means actuated by the set indicating-actuators and in inoperative relation with the unset indicating-actuators.

26. The combination with an endless jacquard-belt, of a circuit of settable indicating-actuators carried by said jacquard-belt, 25 and normally unset; means for actuating the jacquard-belt; and means actuated by the set indicating-actuators and in inoperative relation with the unset indicating-actuators.

27. The combination with a jacquard-belt, 30 of a plurality of settable indicating-actuators carried by said jacquard-belt and normally unset; means for actuating the jacquard-belt; key-operated devices for setting a determined number of said indicating-actuators; and means actuated by the set indicating-actuators and in inoperative relation with the unset indicating-actuators.

28. The combination with a jacquard-carrier movable between two extreme positions, 40 of an endless jacquard having two runs progressive around said carrier; a plurality of settable indicating-actuators carried by said jacquard and normally unset; a pair of means operative, respectively, for differentially advancing said respective runs; and means actuated by the set indicating-actuators and in inoperative relation with the unset indicating-actuators.

29. The combination with a jacquard-belt, 50 of a plurality of settable indicating-actuators carried by said jacquard-belt and normally unset; means for actuating the jacquard-belt; means actuated by the set indicating-actuators and in inoperative relation with the unset indicating-actuators; and resetting means for restoring the set indicating-actuators to their normal positions.

30. The combination with an endless jacquard having two progressive runs, of a plurality 60 of settable indicating-actuators carried by one of said runs and normally unset; means for advancing said runs; means actuated by the set indicating-actuators and in inoperative relation with the unset indicating-actuators; and resetting means between the actuated means and the setting means

for restoring the set indicating-actuators to their normal positions.

31. The combination with a jacquard-belt, 70 of a plurality of transversely-separated longitudinal series of settable indicating-actuators carried by said jacquard-belt and normally unset; means for actuating the jacquard-belt; a plurality of key-operated devices, one for each series of indicating-actuators and operative, respectively, for setting the actuators of their respective series of indicating-actuators; and means actuated by the set indicating-actuators and in inoperative relation with the unset indicating-actuators.

32. The combination with a jacquard-belt, 80 of a plurality of settable indicating-actuators carried by said jacquard-belt and normally in their unset positions and shiftable to their set positions; means for actuating the jacquard-belt; and a plurality of independently-operative devices actuated by the set indicating-actuators and in inoperative relation with the unset indicating-actuators.

33. The combination with a jacquard-belt, 90 of a plurality of transversely-separated longitudinal series of settable indicating-actuators carried by said jacquard-belt and normally unset; means for actuating the jacquard-belt; 95 and a plurality of independently-operative devices, one for each series of indicating-actuators and actuated, respectively, by the set actuators of their respective series of indicating-actuators and in inoperative relation with the unset indicating-actuators.

34. The combination with a jacquard-belt, 100 of a plurality of transversely-separated longitudinal series of settable indicating-actuators carried by said jacquard-belt and spaced equidistantly longitudinally thereof and normally unset; means for actuating the jacquard-belt; and a plurality of independently-operative devices, one for each series of indicating-actuators and actuated, respectively, 105 by the set actuators of their respective series of indicating-actuators and in inoperative relation with the unset indicating-actuators.

35. The combination with a jacquard-belt, 110 of a plurality of transversely-separated longitudinal series of settable indicating-actuators carried by said jacquard-belt and spaced equidistantly longitudinally thereof and normally unset and disposed also in transverse series perpendicular to such longitudinal series; means for actuating the jacquard-belt; 120 and a plurality of independently-operative devices, one for each longitudinal series of indicating-actuators and actuated, respectively, by the set actuators of their respective longitudinal series of indicating-actuators and in inoperative relation with the unset indicating-actuators.

36. The combination with a jacquard-belt and with means for actuating the same, of 130 normally-unset primary jacquard-belt-actuated means normally in inoperative relation

with secondary actuated means and settable by the jacquard-belt in position for operating such secondary actuated means; secondary actuated means operable by said primary jacquard-belt-actuated means; means for reciprocating said primary jacquard-belt-actuated means between its operated and operating positions; and resetting means for restoring the primary jacquard-belt-actuated means to its 10 normal unset position after the operation thereof.

37. The combination with a jacquard and with means for actuating the same, of normally - unset primary jacquard - actuated means normally in inoperative relation with secondary actuated means and settable by the jacquard in position for operating such secondary actuated means; secondary actuated means operable by said primary jacquard-actuated means; means for oscillating said primary jacquard-actuated means between its operated and operating positions; and resetting means for restoring the primary jacquard-actuated means to its normal unset position after the operation thereof.

38. The combination with a jacquard and with means for actuating the same, of normally-unset primary means normally in inoperative relation with secondary means and settable by the jacquard in position for operating such secondary means; secondary means operable by said primary means; means for actuating such primary means to its operated and operating positions, alternately; and resetting means normally out of the path of the primary means and operative into engagement with said actuated means on the return of such actuated means to its operated position, for restoring the primary 40 means to its normally-unset position after the operation thereof.

39. The combination with a jacquard, of a plurality of settable indicating-actuators carried by said jacquard and normally unset; means for actuating the jacquard; normally-unset primary jacquard-actuated means in inoperative relation with the unset indicating-actuators and normally in inoperative relation with secondary actuated means and settable by the set indicating-actuators in position for operating such secondary actuated means; secondary actuated means operable by the said primary jacquard - actuated means; means for actuating said primary jacquard-actuated means to its operated and operating positions alternately; and resetting means for restoring the set indicating-actuators and primary jacquard-actuated means to their normal unset positions after 60 operation.

40. The combination with a jacquard, of a plurality of transversely-separated longitudinal series of settable indicating-actuators carried by said jacquard and normally unset; means for actuating the jacquard; a series of normally-unset independently-settable primary jacquard-actuated devices, one for

each series of indicating-actuators and in inoperative relation, respectively, with the unset actuators of their respective series of indicating-actuators and normally in inoperative relation, respectively, with their respective secondary actuated devices and settable, respectively, by the set actuators of their respective series of indicating-actuators in position for operating their respective secondary actuated devices; a series of independently-operative secondary actuated devices, one for each primary jacquard-actuated device and operable, respectively, by their respective primary jacquard-actuated devices; means for simultaneously actuating all of said primary jacquard-actuated devices to their operated and operating positions, alternately; and resetting means for restoring the primary jacquard-actuated devices to their normal unset positions after operation.

41. The combination with a jacquard, of a plurality of transversely-separated longitudinal series of settable indicating-actuators carried by said jacquard and normally unset; means for actuating the jacquard; and a plurality of resetting members, one for each series of indicating-actuators and operative, respectively, for restoring the set actuators of their respective series of indicating-actuators to their normal positions after operation.

42. The combination with a jacquard, of a plurality of transversely-separated longitudinal series of settable indicating-actuators carried by said jacquard and normally unset; means for actuating the jacquard; and a resetting-comb disposed transversely of the jacquard and having a plurality of resetting members, one for each series of indicating-actuators and aligned, respectively, with said respective series and operative, respectively, for restoring the actuators of their respective series of indicating-actuators to their normal positions after operation.

43. The combination with a jacquard, of a plurality of transversely-separated longitudinal series of settable indicating-actuators carried by said jacquard and normally unset; a plurality of key-operated devices, one for each series of indicating-actuators and operative, respectively, for setting the actuators of their respective series of indicating-actuators; means for actuating the jacquard; and a plurality of devices actuated by the jacquard, one for each series of indicating-actuators and operative, respectively, by the set actuators of their respective series of indicating-actuators and in inoperative relation with the unset indicating-actuators.

44. The combination with a jacquard, of a plurality of transversely-separated longitudinal series of settable indicating-actuators carried by said jacquard and spaced equidistantly longitudinally thereof and normally unset; a plurality of independently-operative key-operated devices, one for each series of indicating-actuators and selectively operative for successively setting the actuators of

- their respective series of indicating-actuators; and means for actuating the jacquard an interval between two indicating-actuators on each operation of a key.
- 5 45. The combination with a jacquard having two progressive portions, of means for advancing one of said portions; and a combined jacquard-actuating and jacquard-actuated apparatus having its jacquard-actuating movement operative for independently actuating the other portion of the jacquard and receiving its jacquard-actuated movement from said other portion of the jacquard on the operation of such portion.
- 15 46. The combination with an endless jacquard having two differentially-progressive runs and also having a plurality of settable indicating-actuators normally unset, of the following instrumentalities successively operative in the order named, viz: means for setting a determined number of the indicating-actuators of the first run; and means for advancing said run a determined distance; and the following instrumentalities successively operative in the order named, viz: means for advancing the second run of the jacquard differentially relatively to the advance of the first run; and means actuated at said second run by such set indicating-actuators.
- 25 47. The combination with an endless jacquard having two differentially-progressive runs and also having a plurality of settable indicating-actuators normally unset, of the following instrumentalities successively operative in the order named, viz: means for setting a determined number of indicating-actuators of the first run; and means for advancing said first run a determined distance; and the following instrumentalities successively operative in the order named, viz: means for advancing the second run of the jacquard differentially relatively to the advance of the first run; means actuated at said second run by such set indicating-actuators; and resetting means for restoring such set indicating-actuators to their normal unset positions.
- 35 48. The combination with an endless jacquard having two differentially-progressive runs and also having a plurality of settable indicating-actuators normally unset, of the following instrumentalities successively operative in the order named, viz: means for setting a determined number of the indicating-actuators of the first run; and means for advancing said first run a determined distance; and the following instrumentalities successively operative in the order named, viz: means for advancing the second run of the jacquard differentially relatively to the advance of the first run; normally unset primary actuated means settable at said second run by such indicating-actuators; secondary actuated means operative by such primary actuated means; and resetting means for resetting the primary jacquard-actuated means to the normal unset position thereof.
49. The combination with a jacquard and with means for actuating the same, of a tumbler-carrier; and an oscillatory tumbler carried by said carrier and normally in its unset position and settable by the jacquard, whereby said tumbler is oscillated to its set position.
50. The combination with a jacquard and with means for actuating the same, of a tumbler-carrier; and a plurality of independently-oscillatory tumblers mounted on said carrier and normally in their unset positions and settable by the jacquard, whereby said tumblers are oscillated to their set positions.
51. The combination with a jacquard and with means for actuating the same, of a tumbler-carrier bar; tumbler-separating members; a tumbler-carrier carried by said bar; and a plurality of independently-oscillatory tumblers mounted on said tumbler-carrier and normally in their unset positions and settable by the jacquard, whereby said tumblers are oscillated to their set positions.
52. The combination with a jacquard and with means for actuating the same, of a tumbler-carrier bar; alined tumbler-separating members formed with registering apertures; a tumbler-carrier carried by said bar and passed through said apertures; and a plurality of independently-oscillatory tumblers mounted on said tumbler-carrier and normally in their unset positions and settable by the jacquard, whereby said tumblers are oscillated to their set positions.
53. The combination with a jacquard and with means for actuating the same, of a tumbler-carrier bar; alined tumbler-separating members fixed on said bar and formed with registering apertures; a tumbler-carrier carried by said bar and passed through said apertures; and a plurality of independently-oscillatory tumblers mounted on said tumbler-carrier and normally in their unset positions and settable by the jacquard, whereby said tumblers are oscillated to their set positions.
54. The combination with a jacquard and with means for actuating the same, of devices for stopping the tumblers in their set and unset positions, alternately; a tumbler-carrier; and a plurality of independently-oscillatory tumblers carried by said tumbler-carrier and normally in their unset positions and settable by the jacquard, whereby said tumblers are oscillated to their set positions.
- 55 55. The combination with a jacquard and with means for actuating the same, of a tumbler-carrier bar; devices carried by said bar for stopping the tumblers in their set and unset positions, alternately; a tumbler-carrier carried by said bar; and a plurality of independently-oscillatory tumblers mounted on said tumbler-carrier and normally in their unset positions and settable by the jacquard, whereby said tumblers are oscillated to their set positions.
- 60 56. The combination with a jacquard and with means for actuating the same, of a

- tumbler-carrier bar; tumbler-separating members carried by said bar; devices also carried by said bar for stopping the tumblers in their set and unset positions, alternately; 5 a tumbler-carrier also carried by said bar; and a plurality of independently-oscillatory tumblers mounted on said tumbler-carrier and normally in their unset positions and settable by the jacquard, whereby said tumblers are oscillated to their set positions. 10
57. The combination with a jacquard and with means for actuating the same, of a tumbler-carrier bar; tumbler-separating members carried by said bar; tumbler-stops also 15 carried by said bar and between said tumbler-separating members for stopping the tumblers in their set and unset positions, alternately; a tumbler-carrier also carried by said bar; and a plurality of independently- 20 oscillatory tumblers mounted on said tumbler-carrier and normally in their unset positions and settable by the jacquard, whereby said tumblers are oscillated to their set positions. 25
58. The combination with a jacquard and with means for actuating the same, of a tumbler-carrier bar; alined tumbler-separating members carried by said bar and formed with registering apertures; tumbler-stops also carried by said bar for stopping the tumblers in their set and unset positions, alternately; a tumbler-carrier also carried by said bar and passed through the apertures in said tumbler-separating members; and a plurality of independently-oscillatory tumblers mounted on 30 said tumbler-carrier and normally in their unset positions and settable by the jacquard, whereby said tumblers are oscillated to their set positions. 35
59. The combination with a jacquard and with means for actuating the same, of a tumbler-carrier bar; alined tumbler-separating members carried by said bar and formed with registering apertures; a plurality of tumbler- 40 stops also carried by said bar, one pair between each pair of tumbler-separating members, for stopping the tumblers in their set and unset positions, alternately; a tumbler-carrier also carried by said bar and passed 45 through the apertures in said tumbler-separating members; and a plurality of independently-oscillatory tumblers mounted on said tumbler-carrier and normally in their unset positions and settable by the jacquard, 50 whereby said tumblers are oscillated to their set positions. 55
60. The combination with a jacquard, of a plurality of settable indicating-actuators carried by said jacquard and normally unset; 60 means for actuating the jacquard; a tumbler-carrier; and a plurality of independently-oscillatory tumblers carried by said carrier and in inoperative relation with the unset indicating-actuators and normally in their unset 65 positions and settable by the set indicating-actuators, and each having a face inclined to- ward the jacquard and adapted to be engaged by its respective indicating-actuator and carried away from the jacquard, to thereby oscillate the tumbler to its set position. 70
61. The combination with a jacquard, of a plurality of settable indicating-actuators carried by said jacquard and normally unset; means for actuating the jacquard; a tumbler-carrier; and a plurality of independently- 75 oscillatory tumblers carried by said carrier and in inoperative relation with the unset indicating-actuators and normally in their unset positions and settable by the set indicating-actuators, and each having a chan- 80 neled face inclined toward the jacquard and adapted to be engaged by its respective indicating-actuator and carried away from the jacquard to thereby oscillate the tumbler to its set position, and each tumbler also hav- 85 ing its channel in the path of its set indicating-actuator to thereby guide said actuator between the walls of said channel. 90
62. The combination with an endless jac- quard having two differentially-progressive runs, of means for recording successive indications on the first of said runs at determined points transversely of said run; means for actuating said run a determined distance on each recordation of an indication; means for 95 advancing the second run of the jacquard differentially relatively to the advance of the first run; a plurality of selectively settable primary devices controlled at the second run by said indications and operative independ- 100 ently of the movement of the first run; and a plurality of levers, one for each primary device, and operative, respectively, by said respective primary devices. 105
63. The combination with an endless jac- quard having two differentially-progressive runs, of means for recording successive indications on the first of said runs at determined points transversely of said run; means for actuating said run a determined distance on 110 each recordation of an indication; means for advancing the second run of the jacquard differentially relatively to the advance of the first run; a plurality of selectively settable primary devices controlled at the second run 115 by said indications and operative independ- 120 ently of the movement of the first run; a plu- rality of levers, one for each primary device, and operative, respectively, by said respec- tive primary devices; a plurality of type- 125 arms connected, respectively, with said res- pective levers; a universal bar operative by said levers; a type-writer carriage; and car- rige-feeding mechanism operative by said universal bar. 125
64. The combination with an endless jac- quard having two differentially-progressive runs, of a plurality of settable indicating-actuators carried by said jacquard and nor- mally unset; a plurality of key-operated set- 130 ting devices for selectively setting success- ively-determined actuating-indicators; a

universal bar operative by said setting devices; means operative by said universal bar for intermittently advancing the first run a determined distance on each setting; means for advancing the second run of the jacquard differentially relatively to the advance of the first run; and a plurality of selectively set-

table devices operative at the second run by the set indicating -actuators independently of the movement of the first run.
